ABSTRACT OF THE DISCLOSURE

A spark gap switch is provided with three adjustable electrodes making it useful over a wide range of voltages and making it possible to readjust the gap spacings between the trigger electrode and the main electrodes and between the main electrodes themselves. The trigger electrode is further provided with a sealed source of radioactive material which stabilizes the flashover voltage value and insures consistency by nullifying the effect of any random ionization in the gaps. The electrodes are further arranged to produce magnetic movement of the arc away from critical surfaces. The spark gap switch is also provided with terminals at opposite ends of the switch to make high voltage connection possible from either end.

Background of the invention

This invention relates to spark gap switches, and more particularly relates to spark gap switches which can be adjusted with great ease and precision.

Precision spark gap switches have numerous uses. For example, high speed circuit breakers have been developed using discharge capacitors which discharge into various types of coils to produce very rapid physical response of the circuit breaker tripping mechanism. To accomplish this, it is required that a charged capacitor be connected to a coil by an extremely fast switch such as a spark gap having high current capacity to accommodate the high discharge current of the capacitor which can often exceed 10,000 amperes peak. The gap must also withstand the capacitor voltage which could be from 1.5 kv. to 15 kv. The spark gap switch must respond rapidly and reliably to protect the capacitor.

A spark gap can fulfill the needs of a high capacity, high speed (essentially zero time) switch for use in such circuit breakers, but such gap, to be practical, must have sufficient adjustability to be usable over a wide range of voltages. Such spark gap switches have not heretofore been commercially available.

Spark gap switches have previously been used in high voltage transmission lines to protect series capacitors in the lines by by-passing such capacitors when the voltages are above an acceptable level.

While this application of spark gaps to cause instantaneous by-passing of capacitors when the voltage exceeds a predetermined value, and thereby discharging the capacitors across the spark gap circuit, is known, serious problems exist in adapting these spark gap switches for use in high speed circuit breakers.

A serious problem existing in the field of spark gap switches is that the spark gap devices in the past have been manufactured with specific voltage requirements so that they cannot be used economically in situations where the voltage requirements change. In addition, these spark gap devices have limited useful lives since the arcs between the electrodes of these devices cause erosion of the electrodes and thereby change the spark-over characteristics of the spark gap. The change in spark-over char-

2

acteristics of the particular device makes it unsuitable for the particular situation for which it was designed.

Several methods have been used in the past to attempt to solve these problems, but they have had only limited success. One method used in the past has been the use of an adjustable precision spark gap as shown in U.S. Pat. No. 3,229,145 to O. Jensen and assigned to the assignee of the instant invention. This device, however is a two terminal spark gap and is, therefore, not designed to be triggered. Furthermore, in this device the terminal electrodes are situated at opposite ends of the device and these electrodes have limited accessibility since they are frequently situated so that one may be inaccessible.

Another method shown in U.S. Pat. No. 3,259,792 to O. Jensen and assigned to the assignee of the instant invention employs a three terminal spark gap device in which the two outer terminals are adjustable. In this device, however, it is merely the outside electrodes which are controllable and there is no independent control of the triggering electrode.

The instant invention solves the problems previously existing by providing a spark gap device with a novel arrangement of three adjustable electrodes.

In one embodiment of the invention a novel spark gap switch is provided with three adjustable electrodes. The two outer electrodes are provided with special arc resistant conductive material such as Elkonite, a trademark of P. R. Mallory & Co., tungsten or the like. The separation between these two electrodes constitutes the main spark gap. The two electrodes are adjustable so that the spark gap may be shortened or enlarged to provide for changed voltage requirements or for changes necessitated by any flashover characteristic changes due to electrode erosion. The novel spark gap device is provided with an adjustable third electrode. This electrode constitutes the trigger electrode and is adjustable independently of the other two electrodes. The trigger electrode is also provided with a sealed source of radioactive material, such as radioactive Cobalt-60, to establish a basic ionization level within the spark gap which is significantly greater than the stray ionization in the gap and thereby stabilizes the flashover value and insures consistency.

It is one object of the instant invention to provide a novel spark gap switch usable over a wide range of voltages.

It is another object of this invention to provide a spark gap switch capable of carrying high currents.

It is a further object of this invention to provide a spark gap switch usable in a high speed circuit breaker employing discharge capacitors.

Another object of this invention is to provide a spark gap switch having three adjustable electrodes so that the flashover voltage between the main electrodes and the flashover voltage between the trigger electrode and a main electrode may be adjusted independently.

Another object of this invention is to provide a spark gap switch which may be adjusted to produce desired flashover characteristics even after there has been electrode erosion due to long use.

A further object of this invention is to provide a spark gap switch with electrodes having arc resistant tips to insure their long life.

Another object of this invention is to provide a spark gap switch with means to produce magnetic movement of the arc away from critical surfaces thus prolonging the useful life of the device by preventing electrode erosion.

Another object of the instant invention is to provide a spark gap device including a triggering electrode which improves the consistency of the spark-over voltage of the gap by establishing a basic ionization level within

the gap which is significantly greater than stray ionization which may occur within the gap.

It is another object of this invention to provide a novel precision spark gap switch having electrodes which are accessible at either of two ends for high voltage connection.

It is a further object of this invention to provide a spark gap switch which is economical in that it has a long life and it is simple and inexpensive to manufacture.

These and other objects of this invention will become apparent from the following description when taken in connection with the drawing.

FIG. 1 shows a side cross-sectional view of a spark gap constructed in accordance with the present invention; and

FIG. 2 shows a cross-sectional view of the spark gap switch taken along line 2-2 of FIG. 1.

Referring to the drawings, there is shown the novel spark gap of the invention as comprised of a cylindrical housing 11 of Lucite or other suitable transparent material. One end of housing 11 is supported by epoxy top plate 12 which is designed with mounting holes (not shown) so that it may be secured to a suitable surface. The other end of housing 11 is supported by bottom plate 13.

The main electrode terminals 14 and 15 are formed of high activity bolts which are supported by top plate 12 and bottom plate 13 and secure the plates 12 and 13 to housing 11. Terminals 14 and 15 are accessible from either the top or bottom of the device, thus making circuit connection easier even if the top or bottom of the device is covered or inaccessible when the device is mounted. The electrode terminals 14 and 15 are threaded at both ends to permit their secure mounting to plate 12 by nuts 16 and 17, respectively, and to plate 13 by nuts 18 and 19. The electrode terminals 14 and 15 slidably fit into holes in plates 12 and 13 so that they may be moved when the nuts at their respective ends are not in engagement with the surfaces of plates 12 and 13. The electrode terminals 14 and 15 also each include an enlarged central body 21 and 22, respectively.

Electrode arms 23 and 24 are formed of bent beryllium copper prestressed straps provided with suitable mounting holes and are secured to electrode terminals 14 and 15, respectively, by means of nuts 25 and 26, respectively. The lower ends of electrode arms 23 and 24 are provided with arc resistant tips 27 and 28, respectively, which may be Elkonite or other suitable material.

The spark gap switch includes a third electrode 30. The electrode 30 is the trigger electrode of the spark gap switch. This electrode includes a sealed compartment for housing radioactive material 31. The radioactive material 31 may be Cobalt-60. The trigger electrode 30 also includes a tip 32 which may also be made of arc resistant material such as Elkonite. The trigger arm 30 includes a threaded portion 33 and a head 34 which may be of a hexagonal shape.

The trigger electrode 30 adjustably fits into cylindrical member 35 by means of its threaded portion 33 and the nut 36 attached to the end of member 35. At the opposite end of member 35 is a cylindrical tapered portion 37. This tapered portion 37 may be made of nylon or other suitable material. The cylindrical tapered portion 37 includes a threaded hole through which the threaded portion 33 of trigger electrode 30 passes. The member 35 also includes a pair of threaded portions 38 separated by a pair of flat surfaces (not shown). Threaded portions 38 engage the threaded portion of a hole in top plate 12 and nut 40 to secure the member 35 and its cylindrical tapered portion 37 in place. The flat surfaces are engageable by a wrench or the like for adjusting the position of member 35 and its tapered portion

37. The member 35 and its tapered portion 37 are made of suitable insulation material.

In the novel spark gap switch described all three electrodes are adjustable to control the breakdown voltage necessary to produce flashover in the spark gap. 5 By means of the adjustment of member 35 by the screw action of its thread 38 and the thread in top plate 12 and nut 40, the tapered cylindrical portion 37 may be moved. The movement of tapered portion 37 adjusts 10 the distance between the main electrodes 27 and 28 by means of the creepage of straps 23 and 24 along the tapered member 37.

Trigger electrode 30 may also be adjusted by means of the screw action of its thread 33 and the nut 36 and the threaded hole of member 35.

It is, therefore, seen that the breakdown voltage between the trigger electrode 30 and the electrode arms 23 and 24 may be independently adjusted and the breakdown voltage between the electrode arms 23 and 24 15 may be independently adjusted.

When there is a flashover in the gap between the electrode arms 23 and 24 a concentrated magnetic field is established in the region between the electrode arms as a result of the current flowing through these electrode arms. 25 The magnetic field in the region causes the magnetic movement of the arc between electrode tips 27 and 28 away from the critical surfaces by means of the blowout effect. This magnetic field is established as a result of the U-shaped relationship of the contact 30 arms 23 and 24.

The spark gap switch operates so that under a predetermined voltage condition, the voltage between the trigger electrode 30 and one of the main terminals 14 or 15 is sufficient to cause a flashover between tip 32 and tip 27 or 28. The flashover ionizes the gases in the spark gap between tips 27 and 28 and, hence, permits a flashover between these two tips to short any circuit connected across the terminal electrodes 14 and 15.

The instant invention provides a novel spark gap switch 40 which is easy to manufacture and assemble and has a wide range of voltages over which it is usable. For instance, the instant invention may be made adjustable over a voltage range from 1.5 kv. to approximately 15 kilovolts.

Although the instant invention has been described with respect to a preferred embodiment thereof, it should be understood that many variations and modifications will now be obvious to those skilled in the art, and it is preferred, therefore, that the scope of this invention not be limited by the specific disclosure herein, but only by the appended claims.

The embodiments of the invention in which an exclusive privilege or property is claimed are defined as follows:

1. A spark gap switch comprising:
a main support body;
first and second arcing electrodes connected to said main support body and held in spaced relation to one another;
a third electrode disposed adjacent to and spaced from at least one of said first and second arcing electrodes; 55
adjustable support means connecting said third arcing electrode to said main support body; said adjustable support means comprising a cylinder extending through said main support body and a central shaft extending through said cylinder; said cylinder being longitudinally movable with respect to said main support body; one end of said cylinder connected to at least one of said first or second arcing electrodes and moving said at least one of said first and second arcing electrodes with respect to the other responsive to longitudinal movement of said cylinder;
said third electrode connected to the end of said shaft adjacent said one end of said cylinder and being longitudinally movable with respect to said cylinder, thereby to alter the position of said third electrode

with respect to said at least one of said first and second arcing electrodes.

2. A spark gap switch as defined in claim 1 wherein said main support body includes first and second end plates and first and second bolts, each of said bolts being accessible on the exterior side of either of said end plates; said first and second bolts being connected to said first and second arcing electrodes, respectively.

3. A spark gap switch as defined in claim 1 wherein said first and second arcing electrodes define a U-shaped current path thereby setting up an electromagnetic field which causes magnetic movement of any arc away from an initial arcing position.

4. A spark gap switch as defined in claim 3 wherein the end of said cylinder of said adjustable support means which is connected to at least one of said first or second arcing electrodes is tapered and wherein each of said first and second arcing electrodes includes a conducting strap which is biased against said tapered end of said cylinder so that longitudinal movement of said cylinder causes movement of said first and second arcing electrodes with respect to each other.

5. A spark gap switch comprising:

a main support body;

first and second arcing electrodes connected to said

5

10

15

20

main support body and held in spaced relation to one another;

said first and second arcing electrodes each including a conducting strap positioned so that said first and second electrodes define a U-shaped current path; adjustable support means comprising a cylinder extending through said main support body and being longitudinally movable with respect to said main support body;

said cylinder having a tapered end which is connected to at least one of said conducting straps of said first or second arcing electrode and moving said at least one of said first or second arcing electrode with respect to the other responsive to longitudinal movement of said cylinder.
